UNITED STATES PATENT OFFICE.

JOHN BERNARD APPLE, OF PHILADELPHIA, PENNSYLVANIA.

HYDROCARBON-BURNER.

SPECIFICATION forming part of Letters Patent No. 323,385, dated August 4, 1885.

Application filed August 20, 1884. (No model.)

To all whom it may concern:

Be it known that I, J. BERNARD APPLE, of the city of Philadelphia, in county of Philadelphia, State of Pennsylvania, have invented 5 a new and useful Improvement in Hydrocarbon-Burners, of which the following is a specification.

My invention has reference to hydrocarbon-burners; and it consists in an annularly-grooved tray having its center provided with a draft-regulating valve and its annular groove with water and oil coils or retorts; further, in the foregoing combined with a hood or cap covering the central draft-valve, but arranged 10 in a manner as to leave an annular passage-way for the air-currents; further, in combining with the foregoing specified parts a combined gas and blast nozzle arranged above and in the center of the said hood or cap; further, 15 in providing the said annularly-grooved tray with peculiarly curved walls, and combining with it water, oil, and steam coils, the latter of which directs the flame up under the two former by means of small jets of steam being 20 allowed to escape from said coil, and in many 25 details of construction, all of which are fully set forth in the following specification, and shown in the accompanying drawings, which form part thereof.

30 The object of my invention is to provide an effective construction whereby the water and oil may be vaporized and utilized in a hydrocarbon-burner with a maximum result, enabling a perfect regulation of the gases generated and heat produced.

35 In the drawings, Figure 1 is a sectional elevation of my improved hydrocarbon-burner as applied to a boiler, and is taken on line $x-x$ of Fig. 2; and Fig. 2 is a plan view of same, 40 with the hood, central nozzle, and boiler removed.

45 A is the tray, and is provided with a horizontal flange, A^2 , on the top, by which the burner, as an entirety, may be supported upon the grate-bars K of the boiler L, or upon brick-work, if desired. The outer walls of the tray 50 are inclined, and the bottom is curved to form the annular groove A' , its inner edge terminating in the knife-edge C; and the center B, located within said edge C, is made perforated and fitted with a damper or valve, D, pivoted

to bottom B at d , and having a crank-pin, D' , to which a rod, D^2 , is pivoted, to enable the valve to be opened or closed.

Located above the valve D and center B is 55 the hood or cap E, made cone-shaped and provided with supporting-feet e, which rest upon the knife-edge C, and are made to catch thereon. By this means the hood is supported some distance above the edge C, leaving an annular 60 passage-way, F, for the passage of the air from valve D to the interior of the tray and from under the hood.

G are coils of pipe for containing water, which is to be converted into steam for use 65 in the burner. These coils are arranged conical to correspond with the walls of the tray, and rest on the ribs g in the bottom of the groove A' , so as to be supported clear of the tray on the bottom, and they being of less 70 diameter than the tray they leave a passage-way between themselves and the wall of said tray also. These coils are made more or less open to allow the heat to pass between each coil as well as up both sides. The water is 75 fed in by the pipe G' , (shown in dotted lines,) and the steam passes off by pipe G^2 .

I is the oil coil-pipe, by which the hydrocarbon gas is generated, and is simply a single coil located within the groove A' of the 80 tray, and concentric with the coils G. The oil is fed to this coil by pipe I' , (shown in dotted lines,) and the hydrocarbon-gas escapes by pipe I^2 .

The hydrocarbon gas is led to the injector 85 J, which feeds a mixture of steam and hydrocarbon oil and vapor through a large pivoted nozzle, J' , located above the hood or cap E, and preferably above its center. Steam from the pipe G' is conveyed to said nozzle J' , also, 90 by a pipe, H^2 , and the supply of gas and steam to said nozzle may be regulated by valves I^3 H^3 , located in pipes I^2 H^2 , which are brought outside of the boiler by putting elbows in them. (See Fig. 2.) The nozzle J' may be 95 turned up or down, as desired, as it is adjustable.

H is a single jet-coil for steam, and is located close to the passage-way F and edge C, and has its jet-orifices h pointing downwardly between the oil-coil I and the bottom of the groove A' , and receives its supply of steam 100

from the pipe G^2 by a pipe, H' , having a valve, H^4 , to regulate its supply.

The operation is as follows: A little oil is allowed to flow into the groove A' of the tray 5 from the nozzle J' , and is ignited. When the steam is generated in coils G , and the oil vaporized in the coils I , the supply of oil for the groove A' is greatly reduced, or shut off altogether, and the mixture of gas, fine spray 10 of hydrocarbon oil in a highly-heated condition, and steam which emerges from the nozzle J' , is directed up or down, as desired, and the escaping oil falls on the hood, and any oil not consumed falls into the groove A' . The 15 steam-jets from coil H cause an increased draft and insure the flame being directed under the coils I and G , as well as above and between them, and the peculiar curve given to the tray causes the flame to traverse the various parts 20 in a most effective manner.

It is evident that more than one oil-coil I might be used, and that instead of the walls of the tray being inclined they may be vertical. The hood might be flat instead of conical, and 25 may be made integral with the tray instead of being removable therefrom, as shown. Therefore while the various parts may be modified or changed without deteriorating the working of the burner in a very material respect, I 30 nevertheless prefer the construction shown.

Having now described my invention, what I claim as new and desire to secure by Letters Patent, is—

1. In a hydrocarbon-burner, a tray having 35 an annular groove, in combination with a draft-regulating valve placed within the center bounded by said groove, and water and oil coils located within said groove, substantially as and for the purpose specified.

40 2. In a hydrocarbon-burner, a tray having an annular groove, in combination with a draft-regulating valve placed within the center bounded by said groove, a hood or cap arranged above said valve, and water and oil 45 coils located within said groove, substantially as and for the purpose specified.

3. In a hydrocarbon-burner, a tray having an annular groove, in combination with a draft-regulating valve placed within the center 50 bounded by said groove, a hood or cap arranged above said valve, a hydrocarbon-nozzle arranged above said hood or cap, and wa-

ter and oil coils located within said groove, substantially as and for the purpose specified.

4. In a hydrocarbon-burner, a tray having 55 an annular groove, in combination with a draft-regulating valve placed within the center bounded by said groove, and water, steam, and oil coils located within said groove, the steam-coils being provided with apertures to direct 60 the flame over the other coils, substantially as and for the purpose specified.

5. In a hydrocarbon-burner, a tray having 65 an annular groove, in combination with water and oil coils, a hood bounded by said groove, and a hydrocarbon-nozzle above said hood, substantially as and for the purpose specified.

6. In a hydrocarbon-burner, a tray having 70 an annular groove, in combination with steam, water, and oil coils, a hood bounded by said groove and a hydrocarbon-nozzle above said hood, the steam-coil directing the flame upon and among the other coils and spraying any oil which runs into the groove, substantially as and for the purpose specified.

7. The tray for a hydrocarbon-burner having 75 annular groove A' and central valved part, B , substantially as and for the purpose specified.

8. The tray for a hydrocarbon-burner having 80 annular groove A' and central valved part, B , in combination with the hood or cap E , hydrocarbon-nozzle above said hood, and air-passage F , substantially as and for the purpose specified.

9. The combination of tray A , having groove A' , flange A^2 , and central valved part, B , substantially as and for the purpose specified.

10. The combination of tray A , having groove A' , valve D , coils G , H , and I , hood E , injector J , and nozzle J' , substantially as and for the purpose specified.

11. The combination of tray A , having groove A' , valve D , coils G , H , and I , hood E , injector J , and nozzle J' , pipes G^2 I^2 H' H^2 , and 95 valves I^3 H^3 H^4 , substantially as and for the purpose specified.

In testimony of which invention I hereunto set my hand.

JOHN BERNARD APPLE.
